GYRATORY SIFTER

Hiram E. Temple, San Gabriel, Calif., assignor
to Read Standard Corporation, a corporation
of Delaware

Application December 5, 1950, Serial No. 199,320

14 Claims. (Cl. 209—315)

1

The present invention relates to a gyratory sifter and will be considered herein in connection with flour sifting for purposes of illustration.

In general, a primary object of the present invention is to provide a gyratory sifter which includes a sifting structure movable in an orbit about a substantially vertical axis of gyration.

Another object is to provide crank means carried by and rotatable relative to a suitable supporting structure for moving the sifting structure in an orbit of constant diameter about a substantially vertical axis of gyration, and which includes means connected to the supporting structure and to the sifting structure for substantially preventing rotation of the sifting structure relative to the supporting structure as it moves in its orbit about the axis of gyration.

An important object is to provide a gyratory sifter of the foregoing character wherein the sifting structure is counterbalanced so as to prevent excessive vibration of the sifter and to prevent excessive transmission of excessive vibration to the building or other structure in which the sifter is installed.

Another important object of the invention is to provide a sifting structure comprising a series of sifting units which are stacked one upon the other and into which unsifted flour is introduced in sequence. In other words, another important object of the invention is to provide a sifting structure having such a series of sifting units in which unsifted flour discharged by any of the sifting units in the series, excepting the last sifting unit in the series, is introduced into the next sifting unit in the series. With this construction, the maximum percentage of flour particles which are small enough to pass through the sifting units is recovered, which is an important feature of the invention.

Another object is to provide a sifting structure in which the sifting units include substantially horizontal annular sifting elements which are pervious to flour particles not exceeding a predetermined size, but impervious to flour particles exceeding this predetermined size and adapted to discharge such oversize particles over their outer peripheries upon orbital movement of the sifting structure about its axis of gyration.

Another important object of the invention is to provide a sifting structure for a gyratory sifter wherein the particles passing through the sifting elements of the sifting units converge toward a central outlet passage means, and wherein the particles discharged over the outer peripheries of the sifting elements descend in an annular, zigzag path.

2

Still another object is to provide discharge conveyor means in each sifting unit above the lowermost for conveying oversize particles discharged over the outer periphery of its sifting element inwardly and downwardly onto the sifting element of the sifting unit therebeneath. A related object is to provide a sifting structure wherein the discharge conveyor means of each sifting unit comprises an inwardly and downwardly sloping funnel carried by an annular housing element of such sifting unit, the sifting element of such sifting unit also being carried by the annular housing element thereof. Thus, such discharge funnels convey the oversize particles discharged by the sifting elements of the sifting units above the lowermost sifting unit onto the sifting elements of the sifting units therebeneath, respectively, whereby a maximum percentage of the siftable particles is recovered.

Another object is to provide a sifting structure which includes a central outlet passage means encircled by the annular sifting units, each sifting unit including an outlet conveyor means below the sifting element thereof for conveying particles passing through the sifting element thereof inwardly and downwardly into such central outlet passage means. A related object is to provide each sifting unit with an outlet conveyor means having the form of a funnel with a central opening which registers with the central outlet passage means.

Another object is to provide each sifting unit with means for vibrating its sifting element to facilitate passage of the flour particles therethrough. Preferably, the vibrating means of each sifting unit includes a plurality of balls adapted to impinge on the sifting element thereof.

While the central outlet passage means referred to above may be a single outlet passage into which the particles passing through all of the sifting elements are conveyed, it will be understood that the central outlet passage means may also include a plurality of outlet passages, such as concentric outlet passages, into which the particles passing through different ones of the sifting elements are respectively conveyed, such an arrangement having utility where it is desired to separate the flour into different grades according to particle size.

Still another object of the present invention is to provide such a sifting structure having a base beneath the stack of sifting units and having a cover above such stack, the cover being provided with an inlet means for the flour to be sifted and the base being provided with an outlet means for the sifted flour and a discharge means for the

flour discharged or rejected by the sifting units. The flour discharged or rejected may consist of lumps of flour, or particles of flour too coarse to pass through the sifting elements.

Still another important object of the present invention is to provide a sifting structure of this character wherein the cover, the sifting units and the base are all readily separable for cleaning.

Another object in connection with the foregoing is to provide a sifting structure wherein the sifting units are merely stacked on each other, the lowermost unit in the stack being seated on the base and the cover being seated on the uppermost unit in the stack. Thus, the various components of the sifting structure may be assembled and disassembled readily by merely stacking and unstacking them. With this construction, the entire sifting structure may be disassembled for cleaning, or for other purposes, in a matter of a very few minutes, which is an important feature.

Another object is to provide interlocking means on the base, sifting units and the cover for maintaining these components of the sifter in axial alignment, a related object being to provide readily releasable means for securing such components together.

Another object is to provide a construction wherein the outlet funnels incorporated in the sifting units above the lowermost unit in the stack engage the respective sifting units therebeneath and are formed of resilient sheet material in a state of upward deformation so that the inherent resilience of such funnels biases them into positive engagement with the sifting units therebeneath. With this construction, no seals between the outlet funnels and the sifting units therebeneath are required, which is an important feature of the invention.

The foregoing objects and advantages of the present invention, together with various other objects and advantages which will become apparent, may be attained with the exemplary embodiments of the invention which are described in detail hereinafter. Referring to the accompanying drawings:

Fig. 1 is an elevation, partially in vertical section, of a gyratory sifter which embodies the invention;

Fig. 2 is a horizontal section taken along the broken line 2—2 of Fig. 1;

Fig. 3 is a fragmentary vertical section taken along the broken line 3—3 of Fig. 2;

Fig. 4 is a fragmentary plan view of part of one of a stack of sifting units incorporated in the sifter of the invention;

Figs. 5 and 6 are fragmentary vertical sections taken along the broken lines 5—5 and 6—6, respectively, of Fig. 4, Fig. 6 being on an enlarged scale;

Fig. 7 is a horizontal section taken along the broken line 7—7 of Fig. 1; and

Fig. 8 is an enlarged vertical section taken along the broken line 8—8 of Fig. 7.

Referring particularly to Fig. 1 of the drawings, the gyratory sifter of the invention includes a sifting structure, indicated generally by the numeral 11, which is carried by any suitable supporting structure, indicated generally by the numeral 12, for orbital movement relative to the supporting structure about an axis of gyration A—A. In the particular construction illustrated, the gyratory sifter includes main crank means 13

for gyrating the sifting structure 11 in its orbit about the axis of gyration A—A, and includes restraining means, exemplified as auxiliary crank means 14, for substantially preventing rotation of the sifting structure relative to the supporting structure 12 upon orbital movement of the sifting structure about the axis of gyration. In order to minimize the transmission of vibration to the building or other structure in which the gyratory sifter is installed, the sifter is provided with means 15 for counterbalancing the sifting structure 11. The main crank means 13, which is rotatable about the axis of gyration A—A to produce orbital movement of the sifting structure 11 about such axis, is adapted to be driven by an electric motor 16 mounted on the supporting structure 12 in the particular construction illustrated.

As a matter of convenience, the components of the gyratory sifter which are associated with the production of orbital movement of the sifting structure 11 about the axis of gyration A—A and with the counterbalancing thereof will be considered in detail before considering the details of the sifting structure 11, such components having utility with other sifting structures than the particular sifting structure 11 described hereinafter, as disclosed in the aforementioned pending application, for example.

Referring particularly to Figs. 1 and 7, the supporting structure 12, in the particular construction illustrated, is of generally triangular configuration and includes three tubular standards 21 interconnected by upper and lower horizontal braces 22 and 23 welded or otherwise secured thereto. The standards 21 are provided at their lower ends with annular flanges 24 for use in bolting or otherwise securing the supporting structure 12 to a floor, or the like. Spanning the space between and welded or otherwise secured to two of the upper horizontal braces 22 is an upper angle 27, and spanning the space between and welded or otherwise connected to the corresponding two lower horizontal braces 23 is a lower angle 28 parallel to and disposed directly below the upper angle 27. Bolted or otherwise secured to the upper and lower angles 27 and 28 are upper and lower bearings 29 and 30, respectively, which are coaxial with the axis of gyration A—A. Disposed in the bearings 29 and 30, which are preferably thrust resisting, is a main crankshaft 31 which forms part of the main crank means 13 and the axis of which coincides with the axis of gyration A—A. The main crankshaft 31 is adapted to be rotated about the axis of gyration A—A by the motor 16 through a belt 32 trained around a pulley 33 secured to the main crankshaft and a pulley 34 secured to the shaft of the motor. The motor 16 is bolted or otherwise secured to a hanger 35 which is pivotally connected, by a pin 36, to upper and lower brackets 37 and 38, respectively, welded or otherwise connected to one of the upper horizontal braces 22 and one of the lower horizontal braces 23. As best illustrated in Fig. 7 of the drawings, the tension in the belt 32 may be regulated by means of an adjusting bolt 39 which is connected to the hanger 35 and to an angle 40 welded or otherwise connected to the same upper and lower horizontal braces to which the upper and lower brackets 37 and 38 are connected. The adjusting bolt 39 has nuts 41 threaded thereonto on opposite sides of one flange of the angle 40 and, as will be apparent, by varying the positions of

these nuts on the adjusting bolt, the hanger 35 with the motor 16 thereon may be rotated about the axis of the pivot pin 36 to adjust the belt tension.

The main crankshaft 31 includes a flexible coupling 46 for absorbing differences in the speed of the motor 16 and the speed of gyration of the sifting structure 11 in its orbit about the axis of gyration A—A. Connected to the upper end of the flexible coupling 46 and forming part of the main crankshaft 31 is an eccentric 47 having a bore 48 therein the axis of which is substantially parallel to but spaced from the axis of gyration A—A of the sifting structure 11. Disposed in the bore 48 is the lower end of an elongated crank pin 49, the lower end of the crank pin being rigidly connected to the eccentric 47, as by a key 50. The axis of the crank pin 49 coincides with the central axis, or axis of symmetry, of the sifting structure 11 in the particular construction illustrated, the axis of the sifting structure being designated as B—B. Encircling the crank pin 49 and rotatably connected thereto by upper and lower bearings 51 and 52, which are preferably thrust resisting, is a sleeve 53 to which the sifting structure 11 is connected, as will be discussed in more detail hereinafter.

As will be apparent, when the main crankshaft 31 is rotated about the axis of gyration A—A by the motor 16, the crank pin 49 moves in an orbit about the axis of gyration A—A, the diameter of such orbit being determined by the distance between the axes A—A and B—B. Thus, the crank pin 49 moves the sifting structure 11 about the axis of gyration A—A in the same orbit to produce the desired orbital movement of the sifting structure. The bearings 51 and 52 permit the crank pin 49 to rotate relative to the sifting structure 11 as the main crankshaft 31 is rotated, thus permitting the sifting structure 11 to remain stationary relative to the supporting structure 12 except for its orbital movement relative thereto about the axis of gyration A—A. In other words, the structure thus far described permits gyration of the sifting structure 11 relative to the supporting structure 12 about the axis of gyration A—A, but does not produce rotation of the sifting structure relative to the supporting structure except for the effect of friction in the bearings 51 and 52.

The effect of such friction is overcome by the restraining action of the aforementioned auxiliary crank means 14. In the particular construction illustrated, the latter includes three auxiliary cranks or crankshafts 56 respectively carried by the standards 21, one of the auxiliary crankshafts 56 being illustrated in detail in Fig. 8 of the drawings. Referring thereto, each crankshaft 56 is carried by bearings 57, which are preferably thrust resisting. These bearings are pressed into a tubular fitting 58, which, in turn, is telescoped into the upper end of one of the standards 21. A flange 59 on the fitting 58 seats on and is preferably bolted to a flange 60 at the upper end of such standard. Each auxiliary crankshaft 56 is provided with an offset crank pin 61, the offset of the crank pin 61 being equal to the distance between the axes A—A and B—B. Each crank pin 61 is rotatably connected to a fitting 62 by a bearing 63, which is also preferably thrust resisting. The fittings 62 are bolted, or otherwise secured, to the sifting structure 11, as best shown in Figure 1 of the drawings.

As will be apparent, the sifting structure 11 is supported by the main crankshaft 31 and the

auxiliary crankshafts 56, which is the reason for employing bearings of the thrust resisting type, as hereinbefore indicated. If desired, the bearings shown may be supplemented by conventional 5 thrust bearings, not shown.

Thus, as the sifting structure 11 is moved orbitally about its axis of gyration A—A upon rotation of the main crankshaft 31, it is prevented from rotating relative to the supporting structure 10 12 by the auxiliary crankshafts 56, except for a slight rotary oscillation resulting from rotation of the auxiliary crankshafts.

As previously indicated, the sifting structure is counterbalanced to prevent excessive vibration 15 transmission to a floor or other structure on which the supporting structure 12 is mounted, the counterbalancing means 15 counterbalancing the sifting structure 11 at both its upper and lower ends, which is an important feature of the 20 invention. More particularly, the counterbalancing means 15 includes two substantially equal counterweights 66 and 67 respectively located at the lower and upper ends of the crank pin 49. The counterweight 66 is carried by an arm 68 25 which is rigidly connected to the eccentric 47, as by being formed integrally therewith. The upper counterweight 67 is carried by an arm 69 which is rigidly connected to a hub 70, as by being formed integrally therewith. The upper end of 30 the crankpin 49 is inserted into a bore in the hub 70, the latter being fixed on the crank pin, as by a key 71. The counterweights 66 and 67 are vertically aligned and, as best shown in Fig. 7 of the drawings, are disposed diametrically opposite 35 the crank pin 49 with respect to the axis of gyration A—A, the counterweights being maintained in vertical alignment because of the fixed connections between the crank pin 49 and the eccentric 47 and between the crank pin and the hub 70. Thus, it will be apparent that, by counterbalancing the sifting structure 11 at both the upper and lower ends thereof in this manner, vibration of the entire gyratory sifter is minimized. Other counterbalancing means are 40 45 closed in the aforementioned co-pending application.

Turning now to a consideration of the details of the sifting structure 11, and referring particularly to Fig. 1 of the drawings, the sifting structure is of cylindrical configuration in the particular construction illustrated and includes a base 75, a stack of sifting units 76 and a cover 77, the stack of sifting units being seated on the base and the cover being seated on the stack of sifting units. With the exception of the lowermost sifting unit in the stack, each sifting unit is seated on the one therebeneath, the lowermost sifting unit being seated on the base 75.

The base 75 includes a central hub 81 which 60 receives the lower end of the sleeve 53 encircling the crank pin 49. The base 75 also includes an annular rim 82 which is connected to the hub 81 by a disc or web 83, the disc 83 sloping generally outwardly and downwardly from the hub to the rim, and being imperforate except as hereinafter indicated. In the particular construction illustrated, the hub 81, the rim 82 and the disc 83 take the form of a single casting.

The fittings 62 associated with the auxiliary crankshafts 56 are connected to the base 75 of the sifting structure 11, as by cap screws 84. As best shown in Fig. 1 of the drawings, the base 75 may be provided with depending bosses 85 into which the screws 84 are threaded. Thus, the sifting structure 11 is supported by the standards

21 through the auxiliary crankshafts 56 and the elements associated therewith.

Each sifting unit 76 includes an annular housing element 88 which is illustrated as being of the same diameter as the annular rim 82 of the base 75. Each housing element 88 is provided on its upper edge with an annular, upwardly extending tongue 89 which is received in a complementary groove in the lower edge of the housing element thereabove. The annular rim 82 is provided with a similar tongue 89 which is received by a complementary groove in the lower edge of the lowermost housing element 88. The tongue 89 on the upper edge of the uppermost housing element 88 in the stack fits into a complementary groove in the lower edge of an annular rim 91 of the cover 77.

Thus, as will be apparent, when the sifting units 76 and the cover 77 are stacked on the base 75 in the order illustrated in Fig. 1 of the drawings, the tongue-and-groove connections between the base 75 and the lowermost housing element 88, between adjacent housing elements, and between the uppermost housing element and the cover serve to retain the entire assembly in axial alignment with respect to the axis B—B of the sifting structure 11. Consequently, the sifting structure may be assembled readily by merely stacking the sifting units and the cover on the base 75, as will be apparent. In order to secure the components of the sifting structure 11 together, straps 92 adapted to hook over the lower edge of the annular rim 82 of the base 75 are provided, such straps being tensionable by means of toggle-type locking devices 93 suitably connected to the rim 91 of the cover 77. As will be apparent, the length of the straps 92 depends on the number of sifting units 76 employed, the number of sifting units being variable merely by varying the length of the crank pin 49 and by correspondingly varying the length of the sleeve 53.

In addition to the rim 91, the cover 77 includes a central hub 96 which receives the upper end of the sleeve 53 encircling the crank pin 49, the rim 91 being connected to the hub 96 by a web or disc 97. In the particular construction illustrated, the rim 91, the hub 96 and the web or disc 97 of the cover 77 are formed as a single casting. The disc 97 of the cover is provided with a central recess or well 98 which receives the counterweight 67 and in which this counterweight is rotatable, the well 98 being extended upwardly by an annular flange 99 illustrated as formed integrally with the disc 97. A cap 100 telescopes over the annular flange 99 to completely enclose the counterweight 67.

The cover 77 is provided with an inlet means for the flour or other material to be sifted, such inlet means comprising inlet openings 105 encircled by upwardly extending annular flanges 106 to which flexible conduits, not shown, for delivering the flour into the sifting structure 11 may be connected in any suitable manner. Below each inlet opening 105 is a baffle or diffuser 108 for distributing the flour flowing through such inlet opening over the surface of the uppermost sifting unit 76, the baffles 108 being bolted or otherwise secured to the cover 77.

Turning now to a more detailed consideration of the sifting units 76, and referring particularly to Fig. 1 of the drawings, the sifting units above the lowermost unit in the stack are identical and the lowermost unit is similar thereto. Consequently, only the lowermost sifting unit 76 and

one of the sifting units thereabove will be considered in detail and the lowermost sifting unit will be described by pointing out the differences between it and each sifting unit thereabove.

Connected to the annular housing element 88 of each sifting unit 76 above the lowermost unit in the stack, as by being formed integrally therewith, is a downwardly converging conical wall or funnel 111 which, as will be described in more detail hereinafter, serves as a discharge conveyor means for conveying oversize particles discharged by such sifting unit inwardly and downwardly onto the sifting unit therebeneath. The annular housing element 88 of the lowermost sifting unit 76 in the stack is provided with a similar conical wall 111a, the only difference being that the central discharge opening in the conical wall 111a is of larger diameter than the central openings in the conical walls or discharge funnels 111. Each of the discharge funnels 111 and the conical wall 111a is provided adjacent its periphery with a plurality of circumferentially spaced, upwardly extending bosses 112 each of which is provided with a central, upwardly extending pin 113. Seated on the bosses 112 of each sifting unit 76 and positioned by the pins 113 associated with such bosses is a sifting means 115, the pins 113 extending through suitable openings in the sifting means. All of the sifting means 115, including the sifting means of the lowermost sifting unit 76 are identical so that only one of them will be considered in detail.

Each sifting means 115, as best shown in Figs. 4 to 6 of the drawings, is of annular configuration and includes a spider or spider means 116 having a central annular hub 117 and an angle-shaped rim 118 connected to the hub by spokes 119. Each spider 116 also includes arcuate braces 120 between adjacent spokes 119, each arcuate brace dividing the area between a pair of spokes into inner and outer compartments 121 and 122. As will be discussed in more detail hereinafter, the central opening through the annular hub of each sifting means 115 below the sifting means 115 of the uppermost sifting unit 76 serves as an outlet opening for flour, or other material sifted by the sifting means thereabove. It will be noted that, referring for the moment to Fig. 1 of the drawings, the central openings through the annular hubs 117 are all axially aligned so that such central openings serve as a central outlet passage means 123 for the sifted flour, or other material, as will be further discussed hereinafter.

The sifting means 115 of each sifting unit 76 includes an annular sifting element 125, which may be formed of a fabric, such as silk, or which may be formed of wire screen, for example. The inner periphery of the sifting element 125 of each sifting means 115 is clamped between the annular hub 117 of the corresponding spider 116 and an annular collar 126 which is secured to such annular hub in any suitable manner, as by screws 127. The outer periphery of each sifting element 125 is bent downwardly over the rim 118 of its spider 116 and is secured by a circumferential band or hoop 128, the ends of the latter being connected together by a screw 129, Fig. 4. Preferably, as best shown in Fig. 6, the outer peripheral surface of the rim 118 of each spider 116 is provided with an annular groove 130 to receive the outer periphery of the corresponding sifting element 125 and the retaining hoop 128, thereby providing a substantially flush construction. Thus, the sifting element 125 of each sifting means 115 is retained at its inner and outer per-

ipheries, and is supported intermediate its inner and outer peripheries by the spokes 119 and the arcuate braces 120.

In the event that a fabric such as silk is employed for the sifting elements 125, it is desirable to provide means for vibrating such sifting elements to some extent during operation of the gyratory sifter so as to facilitate passage of the flour, or other material, therethrough. Such vibrating means may take the form of balls 133 disposed in the compartments 121 and 122 provided by the spiders 116. The balls 133 associated with each sifting means 115 are retained by a coarse screen 134 which is secured to the annular hub 117 and the rim 118 of the corresponding spider 116 adjacent its inner and outer peripheries, respectively. Each screen 134 is secured at its inner periphery by a ring 135 attached to the annular hub 117 of the corresponding spider 116 by screws 136, or the like, the inner periphery of each screen thus being clamped between the corresponding hub 117 and the corresponding ring 135. Similarly, the outer periphery of each screen 134 is clamped between the rim 118 of the corresponding spider 116 and a ring 137, the ring 137 being secured by screws 138 or the like. As will be apparent, the balls 133 tend to bounce somewhat during orbital movement of the sifting structure 11 as they roll over the relatively coarse supporting screens 134. Thus, the balls strike the sifting elements 125 to vibrate them and facilitate passage of flour, or other material.

In the event that wire screens, for example, are employed for the sifting elements 125, particularly where coarser grades of flour are being sifted, the balls 133 may be omitted, if desired. With such a construction, the retaining screens 134 for the balls and the rings 135 and 137 for retaining such screens may also be omitted.

As best shown in Fig. 1 of the drawings, the outside diameter of each annular sifting means 115 is less than the inside diameter of the corresponding annular housing element 88 so as to provide therebetween an annular discharge passage means 141 through which any unsifted flour, or other material, discharged over the outer periphery of the corresponding sifting element 125 may flow onto the discharge funnel 111 therebeneath. Each discharge funnel 111 thus conveys the oversize particles discharged over the outer peripheries of the sifting elements 125 inwardly and downwardly onto the respective sifting elements therebeneath, the diameter of the central openings through the discharge funnels 111 exceeding the inner diameters of the sifting elements but being less than the outer diameters thereof so that the flour conveyed by the funnels 111 is deposited on the sifting elements therebeneath intermediate the inner and outer peripheries thereof.

Each sifting unit 76, with the exception of the lowermost unit in the stack, includes a downwardly converging, conical wall or outlet funnel 142 which serves as an outlet conveyor means for conveying the flour, or other material, sifted through the corresponding sifting element 125 inwardly and downwardly into the aforementioned central outlet passage means 123, the latter being defined by the annular hubs 117 of the sifting means 115, as previously discussed. As best shown in Figs. 5 and 6 of the drawings, the outer periphery of each outlet funnel 142 is clamped between the outer ring 137 of the corresponding sifting means 115 and the outer periphery of the

retaining screen 134 for the balls 133 so that the outlet funnel 142 associated with each sifting means 115 may be installed and removed with such sifting means. However, connecting the outlet funnels 142 to the sifting means 115 in this manner is not necessary and the outlet funnels may merely be seated on the supporting bosses 112 beneath the sifting means 115 so as to be installable and removable separately, if desired. This latter construction is particularly desirable in a sifting structure 11 which must be cleaned frequently for sanitation purposes. As will be apparent, if the outlet funnels are separate from the sifting means 115, and if the retaining screens 134 for the balls 133 are not employed, the lower surface of each sifting element 125 is exposed for ready cleaning upon removal of the sifting means of which it forms a part.

Each outlet funnel 142 is provided with a downwardly extending annular flange 144 which encircles the central opening therethrough and which telescopes into the collar 126 on the annular hub 117 of the spider 116 therebeneath, as best shown in Fig. 1 of the drawings. Preferably, the outlet funnels 142 are formed of resilient sheet material, such as sheet metal, and are in a state of upward deformation when the sifting structure 11 is assembled so that the inherent resilience of the outlet funnels 142 seats them firmly on the collars 126 therebeneath, the collars preferably being beveled to provide relatively large areas of contact between them and the outlet funnels. In other words, the vertical distance between the outer periphery of each outlet funnel 142 and the inner periphery thereof is normally less than the spacing between the sifting means 115 so that the funnels 142 are sprung upwardly upon assembly of the sifting structure 11 to seat the funnels firmly on the collars 126. Thus, no seals are necessary between the outlet funnels 142 and the collars 126, which is an important feature.

It will be noted that the sifting means 115 and the outlet funnels 142 merely seat on the supporting bosses 112 and are not secured to the annular housing elements 88 against upward movement. As will be apparent, the sifting means 115 of the lowermost sifting unit 76 is retained by the outlet funnel 142 of the sifting unit thereabove. Similarly, the sifting means 115 and the outlet funnel 142 of each sifting unit 76 above the lowermost is retained by the outlet funnel of the sifting unit thereabove, excepting the uppermost sifting unit in the stack. The outlet funnel 142 and the sifting means 115 of the latter are secured against upward movement by telescoping the collar 126 of such sifting means into an annular collar 145 which extends downwardly from and is illustrated as formed integrally with the cover 77. The collar 145 provides an internal annular shoulder 146 which serves as a seat for the collar 126 of the uppermost sifting means. Thus, when the cover 77 is installed after the sifting units 76 have been stacked, the cover automatically secures the various sifting means 115 and outlet funnels 142 against upward movement in the manner hereinbefore discussed. Also, as the various components are assembled, the outlet funnels 142 are automatically sprung upwardly to provide the desired seals between the outlet funnels and the respective sifting means therebeneath.

As best shown in Figs. 1 to 3 of the drawings, the area between the hub 81 of the base 75 and

the rim 82 thereof is divided into an inner, outlet compartment 151 for sifted flour and an outer, discharge compartment 152 for flour particles too large to pass through the sifting elements 125, the separation between the outlet and discharge compartments 151 and 152 being provided by a circular wall 153, illustrated as formed integrally with the disc or web 83 of the base 75. That portion of the disc or web 83 which defines the lower wall of the inner, outlet compartment 151 is provided with arcuate outlet channels 154 which slope downwardly from high points 155 to outlet openings 156. The directions of downward slope of the outlet channels 154 from the high points 155 to the outlet openings 156 are indicated by arrows 157. Encircling each outlet opening 156 and extending downwardly is an annular flange 158 to which a flexible conduit 159 is connected in any suitable manner, as by being telescoped thereover. The flexible conduits 159 leading from the outlet openings 156 are connected to a common outlet conduit 160, as shown in Fig. 1.

Thus, the outlet channels 154, the outlet openings 156, the flexible conduits 159, and the outlet conduit 160 form an outlet means for sifted flour. It will be noted that the sifted flour conveyed into the central outlet passage means 123 by each of the sifting units 76 above the lowermost sifting unit drops onto that portion of the disc or web 83 of the base 75 which forms the bottom of the inner, outlet compartment 151 and finds its way into the arcuate outlet channels 154, the sifted flour thereafter descending along such channels toward the outlet openings 156. No outlet funnel 142 is provided for the lowermost sifting unit 76 in the stack, the flour passing through the sifting element 125 thereof falling directly onto the bottom of the outlet compartment 151.

That portion of the disc or web 83 of the base 75 which defines the bottom of the outer, discharge compartment 152 is provided with arcuate channels 165 which slope downwardly, as indicated by the arrows 166, from a high point 167 to a discharge opening 168, the channels 165 and the opening 168 providing a discharge means for particles too large to pass through any of the sifting elements 125. The discharge opening 168 is encircled by a downwardly extending, annular flange 169 to which a flexible discharge conduit 170, Fig. 3, may be connected in any suitable manner.

It will be noted that the diameter of the central opening through the conical wall 111a of the lowermost sifting unit 76 is greater than that of the circumferential wall 153 which divides the base 75 into the outlet and discharge compartments 151 and 152 so that any flour particles discharged over the outer periphery of the lowermost sifting means 115 fall downwardly into the discharge compartment 152. Thus, the principal function of the conical wall 111a is merely to carry the bosses 112 for supporting the lowermost sifting means 115. As previously pointed out, the conical walls or discharge funnels 111 are provided with central openings of a diameter considerably less than that of the central opening through the wall 111a, the conical walls or discharge funnels 111 serving to convey oversize particles discharged by the sifting means 115 above the lowermost sifting means inwardly and downwardly onto the sifting means therebeneath, respectively.

It will be noted that while the sifting structure 11 has been illustrated as provided with a single central outlet passage means 123 into which the outlet funnels 142 of all of the sifting units above the lowermost discharge, the sifting structure may be provided with a plurality of central outlet passages, one or more of the outlet funnels 142 discharging into each of such passages. Such a construction would have particular utility in flour mills for separation of the flour particles into a plurality of grades according to particle size.

Considering the operation of the gyratory sifter of the invention, when the motor 16 is energized, the main crankshaft 31 is rotated about the axis of gyration A—A to move the sifting structure 11 in an orbit about the axis of gyration. At the same time, the auxiliary crankshafts 56, while substantially preventing rotation of the sifting structure 11 relative to the supporting structure 12 about the axis B—B of the sifting structure, do produce a rotary oscillation of the sifting structure 11 about the axis B—B through a limited angle. As previously discussed, the sifting structure 11 is counterbalanced to avoid developing excessive vibration.

The foregoing compound movement of the sifting structure 11, i. e., the orbital movement thereof about the axis of gyration A—A and the rotary oscillation thereof about the axis B—B, agitates flour, or other material, on the sifting elements 125 to facilitate passage of siftable particles through the sifting element, such agitation being enhanced by the balls 133 when employed. As previously discussed, the flour, or other material, to be sifted is introduced into the sifting unit through the inlet openings 105 and is deposited first on the sifting element 125 of the uppermost sifting unit 76, being diffused or spread by the baffles 108 to insure even distribution and to prevent damage to the uppermost sifting element. The particles passing through the uppermost sifting element 125 are conveyed to the central outlet passage means 123 by the corresponding outlet funnel 142 and descend through the central outlet passage means into the outlet compartment 151, thereafter descending along the arcuate outlet channels 154 to the outlet openings 156. Any particles or lumps which fail to pass through the uppermost sifting element 125 move outwardly as a result of the aforementioned compound movement of the sifting structure 11 and are discharged over the outer periphery thereof, passing through the uppermost discharge passage means 141 and dropping onto the uppermost discharge funnel 111. The latter conveys such particles and/or lumps inwardly and downwardly and deposits them approximately midway between the inner and outer peripheries of the second annular sifting element 125 in the stack. Additional particles pass through the second sifting element in the series and are conveyed inwardly and downwardly to the central outlet passage means 123, through which they descend in the manner hereinbefore described. Again, any particles failing to pass through the second sifting element 125 are discharged over its periphery and are conveyed onto the third sifting element by the second discharge funnel 111. This process is repeated until the unsifted particles have been discharged over the outer periphery of the lowermost sifting element 125 in the stack, such particles falling into the discharge compartment 152 and then into the

annular discharge channel 165, which conveys them to the discharge opening 168.

Thus, the flour sifted by each sifting element 125 above the lowermost is conveyed inwardly to the central outlet passage means 123, the flour sifted by the lowermost sifting element falling directly into the outlet compartment 151. On the other hand, particles which do not pass through successive sifting elements 125 descend through the sifting structure 11 in zigzag fashion until they either pass through one of the sifting elements, or are ultimately discharged over the outer periphery of the last sifting element in the series and into the discharge compartment 152. With this construction, a maximum percentage of the siftable flour is recovered, which is an important feature.

As will be apparent, the sifting structure 11 may be disassembled for cleaning very readily. In disassembling the sifting structure 11, the first step is to remove the cap 100 covering the counterweight well 98. Subsequently, the upper counterweight 67 may be disengaged from the crank pin 49 and the cover 77 may then be removed after releasing the toggle-type locking devices 93. Thereafter, the sifting units 76 may be removed in sequence. Also, the sifting means 115 and the outlet funnel 142 of each sifting unit may be separated from the housing element 88 thereof, either as a unit, or separately, depending upon whether the outlet funnel is attached to the sifting means, or is separable therefrom, as previously discussed. Thus, all of the elements of the sifting structure 11 are exposed to facilitate cleaning. As will be apparent, the structure may be reassembled by reversing the foregoing procedure.

It will be understood that the number of sifting units 76 employed may vary. For example, if it is not essential that tiny lumps of flour be broken up into their individual particles, a few sifting units 76 employing relatively coarse sifting elements 125 may be employed. On the other hand, if it is desired to break up such tiny lumps to produce an extremely fine sifted product, a larger number of sifting units 76 employing finer sifting elements 125 may be employed. As will be apparent, crank pins and encircling sleeves 53 of different lengths may be provided for different numbers of sifting units.

The gyratory sifter of the invention is capable of sifting flour in large volume and at a high rate. Moreover, this is accomplished with a minimum of vibration transmission to the building or other structure in which the sifter is used.

It will be understood that various changes, substitutions and modifications may be incorporated in the exemplary embodiments hereinbefore disclosed without departing from the spirit of the invention. For example, the sifting structure 11 may be of configurations other than cylindrical, and the central axis B-B thereof need not coincide with the axis of the crank pin 49, but may be spaced therefrom.

The invention is defined by the following claims:

1. In a gyratory sifter, the combination of: a supporting structure; a sifting structure mounted on said supporting structure for orbital movement about a substantially vertical axis of gyration and having a central axis which is substantially parallel to but spaced from said axis of gyration, said sifting structure being provided with a series of substantially horizontal, vertically spaced, annular, sifting elements which

are substantially symmetrical about said central axis and each of which is pervious to particles not exceeding a predetermined size but is impervious to particles exceeding said predetermined size and is adapted to discharge such particles over its outer periphery upon orbital movement of said sifting structure about said axis of gyration, said sifting structure further including means for conveying particles passing through the sifting elements above the lowermost sifting element in said series inwardly and downwardly to a central opening in the sifting element therebeneath, the central openings in said sifting elements communicating with each other to provide a central outlet passage means common to said sifting elements and extending vertically along said central axis through all of said sifting elements; and means for moving said sifting structure in an orbit about said axis of gyration.

2. In a gyratory sifter, the combination of: a supporting structure; a sifting structure mounted on said supporting structure for orbital movement about a substantially vertical axis of gyration and having a central axis which is substantially parallel to but spaced from said axis of gyration, said sifting structure including a stack of substantially horizontal, annular sifting units each of which is substantially symmetrical about said central axis and each of which provides a substantially horizontal, annular sifting element pervious to particles not exceeding a predetermined size, but impervious to particles exceeding said predetermined size and adapted to discharge such particles over its outer periphery upon orbital movement of said sifting structure about said axis of gyration, each of said sifting units above the lowermost sifting unit in said stack including first conveyor means for conveying particles passing through the sifting element thereof inwardly and downwardly to a central opening in the sifting unit therebeneath, the central openings in said sifting units communicating with each other to provide an unobstructed central outlet passage means common to said sifting units and extending vertically along said central axis through all of said sifting units; and each of said sifting units above the lowermost sifting unit in said stack including second conveyor means for conveying particles discharged over the outer periphery of the sifting element thereof inwardly and downwardly onto the sifting element of the sifting unit therebeneath; and means for producing orbital movement of said sifting structure about said axis of gyration, including a crankshaft connected to said sifting structure and extending through said outlet passage means.

3. In a gyratory sifter, the combination of: a supporting structure; a sifting structure mounted on said supporting structure for orbital movement about a substantially vertical axis of gyration and having a central axis which is substantially parallel to but spaced from said axis of gyration, said sifting structure including a stack of substantially horizontal, annular, sifting units each of which is substantially symmetrical about said central axis and each of which provides a substantially horizontal, annular, sifting element pervious to particles not exceeding a predetermined size, but impervious to particles exceeding said predetermined size and adapted to discharge such particles over its outer periphery upon orbital movement of said sifting structure about said axis of gyration, said sifting structure

15

further providing central outlet passage means encircled by said sifting units and adapted to receive particles passing through the shifting elements of at least the sifting units above the lowermost sifting unit in said stack, and said sifting structure still further providing a series of peripheral discharge passage means respectively encircling the sifting elements of said sifting units and adapted to receive particles discharged over the outer peripheries of the respective sifting elements, each of said sifting units above the lowermost sifting unit in said stack including outlet conveyor means for conveying particles passing through the sifting element thereof inwardly and downwardly to said central outlet passage means, and each of the sifting units above the lowermost sifting unit in said stack including discharge conveyor means for conveying particles passing through the peripheral discharge passage means encircling the sifting element of such sifting unit inwardly and downwardly onto the sifting element of the sifting unit therebeneath; and means for producing orbital movement of said sifting structure about said axis of gyration, including a crankshaft connected to said sifting structure and extending through said outlet passage means.

4. A gyratory sifter as defined in claim 3 wherein in each of the sifting units in said stack above the lowermost sifting unit therein is carried by the sifting unit therebeneath and wherein the sifting units are separable from each other, said gyratory sifter including means for securing said sifting units together.

5. A gyratory sifter according to claim 3 wherein in each of said outlet conveyor means includes a funnel having a central opening which registers with said central outlet passage means, and wherein each of said discharge conveyor means includes a funnel having a central opening larger than said central outlet passage means but smaller than said sifting elements.

6. In a sifting structure movable in an orbit about a substantially vertical axis of gyration and having a central axis which is substantially parallel to but spaced from said axis of gyration, the combination of: a stack of substantially horizontal, annular, separable, sifting units each of which is substantially symmetrical about said central axis and each of which provides a substantially horizontal, annular sifting element pervious to particles not exceeding a predetermined size, but impervious to particles exceeding said predetermined size and adapted to discharge such oversize particles over its outer periphery upon orbital movement of said sifting structure about said axis of gyration, each of said sifting units above the lowermost sifting unit in said stack including outlet conveyor means for conveying particles passing through the sifting element thereof inwardly and downwardly toward a central opening in the sifting unit therebeneath, the central openings in said sifting units communicating with each other to provide a central outlet passage means common to said sifting units and extending vertically along said central axis through all of said sifting units, and each of said sifting units above the lowermost sifting unit in said stack including discharge conveyor means for conveying particles discharged over the outer periphery of the sifting element thereof inwardly and downwardly onto the sifting element of the sifting unit therebeneath; and means for releasably securing said separable sifting units together.

16

7. In a sifting structure movable in an orbit about a substantially vertical axis of gyration and having a central axis which is substantially parallel to but spaced from said axis of gyration, the combination of: a stack of substantially horizontal, annular, sifting units each of which is substantially symmetrical about said central axis and each of which includes an annular housing element, each of said housing elements above the housing element of the lowermost sifting unit in said stack being seated on the housing element of the sifting unit therebeneath, the housing element of each of said sifting units carrying a substantially horizontal, annular sifting element pervious to particles not exceeding a predetermined size, but impervious to particles exceeding said predetermined size and adapted to discharge such oversize particles over its outer periphery upon orbital movement of said sifting structure about said axis of gyration, said sifting element of each of said sifting units being spaced inwardly from the housing element thereof to provide a peripheral discharge passage means for particles discharged over the outer periphery of such sifting element, central openings through said sifting units providing central outlet passage means encircled by said sifting units and adapted to receive particles passing through the sifting elements of at least the sifting units above the lowermost sifting unit in said stack, the housing element of each of said sifting units above the lowermost sifting unit in said stack further carrying a downwardly and inwardly sloping funnel below the sifting element thereof for conveying particles passing through the sifting element thereof inwardly and downwardly to said central outlet passage means; a cover seated on the housing element of the uppermost sifting unit in said stack and providing inlet means for the introduction of particles to be sifted into the uppermost sifting unit in said stack; a base on which the housing element of the lowermost sifting unit in said stack is seated, said base being provided with outlet means communicating with said central outlet passage means and being provided with discharge means communicating with said peripheral discharge passage means; and means for securing said base, said sifting units, and said cover together.

8. In a sifting structure movable in an orbit about a substantially vertical axis of gyration and having a central axis which is substantially parallel to but spaced from said axis of gyration, the combination of: a stack of substantially horizontal, annular, sifting units each of which is substantially symmetrical about said central axis and each of which includes an annular housing element, each of said housing elements above the housing element of the lowermost sifting unit in said stack being seated on the housing element of the sifting unit therebeneath, the housing element of each of said sifting units carrying a substantially horizontal, annular, sifting element pervious to particles not exceeding a predetermined size, but impervious to particles exceeding said predetermined size and adapted to discharge such oversize particles over its outer periphery upon orbital movement of said sifting structure about said axis of gyration, said sifting element of each of said sifting units being spaced inwardly from the housing element thereof to provide a peripheral discharge passage means for particles discharged over the outer periphery of such sifting element, central openings through

said sifting units providing central outlet passage means encircled by said sifting units and adapted to receive particles passing through the sifting elements of at least the sifting units above the lowermost sifting unit in said stack, the housing element of each of said sifting units above the lowermost sifting unit in said stack further carrying a downwardly and inwardly sloping funnel below the sifting element thereof for conveying particles passing through the sifting element thereof inwardly and downwardly to said central outlet passage means, and the housing element of each of said sifting units above the lowermost sifting unit in said stack additionally carrying a downwardly and inwardly sloping funnel for conveying particles discharged over the outer periphery of the sifting element of such sifting unit into the corresponding peripheral discharge passage means downwardly and inwardly onto the sifting element of the sifting unit therebeneath, the central openings in the funnels last defined being larger than said central outlet passage means, but smaller than said peripheral discharge passage means; a cover seated on the housing element of the uppermost sifting unit in said stack and providing inlet means for the introduction of particles to be sifted into the uppermost sifting unit in said stack; a base on which the housing element of the lowermost sifting unit in said stack is seated, said base being provided with outlet means communicating with said central outlet passage means and being provided with discharge means communicating with said peripheral discharge passage means; and means for securing said base, said sifting units, and said cover together.

9. In a sifting structure adapted to be gyrated in an orbit about a substantially vertical axis of gyration and having a central axis which is substantially parallel to but spaced from said axis of gyration, the combination of: a stack of annular housing elements substantially symmetrical about said central axis, each of said housing elements above the lowermost housing element in said stack being seated on the housing element therebeneath; a substantially horizontal, annular, sifting element carried by each of said housing elements, each of said sifting elements being concentric with the corresponding housing element and being spaced inwardly therefrom; a funnel carried by each of said housing elements above the lowermost housing element in said stack, said funnels being of substantially the same diameter as said sifting elements and sloping inwardly and downwardly toward central openings in said funnels which register with central openings in the respective sifting elements therebeneath; and another funnel carried by each of said housing elements above the lowermost housing elements in said stack and below the first defined funnel carried thereby, said other funnels being of substantially the same diameter as the outer diameter of the annular spaces between said sifting elements and said housing elements and sloping inwardly and downwardly toward central openings therein of a diameter larger than the inner diameter of said sifting elements.

10. In a sifting structure movable in an orbit about a substantially vertical axis of gyration and having a central axis which is substantially parallel to but spaced from said axis of gyration, the combination of: a substantially horizontal, annular, lower, sifting unit substantially symmetrical about said central axis; and a substan-

tially horizontal, annular upper, sifting unit also substantially symmetrical about said central axis and seated on said lower sifting unit, said upper sifting unit including a funnel which slopes inwardly and downwardly toward a central opening therein which registers with a central opening in said lower sifting unit, said funnel being formed of resilient sheet material and being in a state of upward deformation so that it is biased downwardly into positive engagement with said lower sifting unit by its inherent resilience.

11. In a sifting structure movable in an orbit about a substantially vertical axis of gyration and having a central axis which is substantially parallel to but spaced from said axis of gyration, the combination of: a substantially horizontal, annular, lower, sifting unit substantially symmetrical about said central axis; and a substantially horizontal, annular, upper, sifting unit also substantially symmetrical about said central axis and seated on said lower sifting unit, said upper sifting unit including a funnel which slopes inwardly and downwardly toward a central opening therein which registers with a central opening in said lower sifting unit and which is encircled by an annular flange inserted into the central opening in said lower sifting unit, said funnel being formed of resilient sheet material and the vertical distance between its base and its apex when said funnel is in an undeformed state being greater than the vertical spacing between the central openings in said upper and lower sifting units so that when the annular flange encircling said central opening in said funnel is inserted in said central opening in said lower sifting unit, said funnel is in a state of upward deformation and is therefore biased downwardly into positive engagement with said lower sifting unit by its inherent resilience.

12. A sifting structure as defined in claim 11 wherein said lower sifting unit includes a collar encircling the central opening therein, said annular flange encircling said central opening in said funnel being telescoped into said collar.

13. A sifting structure according to claim 9 wherein the central opening in each of said sifting elements below the uppermost is defined by a collar, and wherein each of the funnels first mentioned in claim 10 is seated on the collar defining the central opening in the sifting element therebeneath, each of said first-mentioned funnels being in a state of upward deformation when said housing elements are stacked and being formed of resilient sheet material so that the inherent resilience thereof biases it downwardly into positive engagement with the collar defining the central opening in the sifting element therebeneath.

14. In a gyratory sifter, the combination of: a supporting structure; a sifting structure mounted on said supporting structure for orbital movement about a substantially vertical axis of gyration and having a central axis which is substantially parallel to and spaced from said axis of gyration, said sifting structure including a stack of substantially horizontal, annular sifting units each of which is substantially symmetrical about said central axis, said annular sifting units being provided with aligned central openings therethrough which cooperate to provide an unobstructed, central passage means common to all of said sifting units and extending vertically along said central axis through all of said sifting units; and means for producing orbital movement of said sifting structure about said axis of gyration, including a crank,

19

shaft connected to said sifting structure and extending through said central passage means.
